UNITED STATES PATENT OFFICE.

WILLIAM MASON, OF NEW HAVEN, CONNECTICUT, ASSIGNOR TO THE
WINCHESTER REPEATING ARMS COMPANY, OF SAME PLACE.

MEANS FOR SEPARABLY UNITING GUN-BARRELS TO THE STOCKS.

SPECIFICATION forming part of Letters Patent No. 487,486, dated December 6, 1892.

Application filed April 4, 1892. Serial No. 427,618. (No model.)

To all whom it may concern:

Be it known that I, WILLIAM MASON, of New Haven, in the county of New Haven and State of Connecticut, have invented a new Improvement in Firearms, (Case A;) and I do hereby declare the following, when taken in connection with accompanying drawings and the letters of reference marked thereon, to be a full, clear, and exact description of the same, and which said drawings constitute part of this specification, and represent, in—

Figure 1, a side view of the receiver portion of the arm complete; Fig. 2, a transverse section of the same on line *x x* of Fig. 1; Fig. 3, a side view of the forward portion of the receiver detached; Fig. 4, a side view of the rear portion of the receiver detached, and Fig. 5 a modification.

This invention relates to an improvement in firearms, and has for its object a convenient construction whereby the barrel may be readily detached from the stock for convenience of packing or transportation.

The invention is applicable alike to breech-loading and magazine firearms; and it consists in making the portion of the receiver which carries the barrel detachable from the remainder of the receiver, which is attached to the stock, combined with mechanism for securely locking the parts together, yet so as to permit their ready separation, as hereinafter described, and particularly recited in the claims.

In illustrating the invention I show the parts of the arm such as contained in the arm known as the "Winchester repeating-firearm." The receiver at its forward end A carries the barrel B and magazine C in the usual manner; but this forward part A, together with the cheeks D D, is made separable from the bottom portion E of the receiver, and this bottom portion E carries at its rear end the tangs F F, by which the stock is attached. The bottom or tang portion E is of width corresponding to the width between the cheeks and so that the two parts may be readily set together, the rear ends of the cheeks abutting against a corresponding shoulder G on the tang portion of the receiver. The forward end of this tang portion or bottom of the receiver terminates in a tenon or projection H, and the for-

ward part of the receiver is constructed with a corresponding recess or mortise I, into which the tenon H will enter as the parts are set together and so as to bring the rear end of the 55 cheeks to abut against the shoulder G at the rear. The projection H and the corresponding recess I interlock the two parts at the forward end against vertical or lateral movement.

To secure the two parts at the rear end, and 60 also to hold them firm against longitudinal movement, a screw is introduced transversely through the cheeks at the rear end and through the part E. Preferably the hammer-pivot is employed as this screw. 65

J represents the hole through the part E near the shoulder, and the cheeks are constructed with corresponding holes K L. Through these holes the screw M is introduced, this screw serving to form the pivot on which 70 the hammer may swing. The hole K in the one cheek is countersunk upon its outside, (see Figs. 2 and 3,) and the screw is constructed with a corresponding conical neck N, and the screw is also provided with a convenient head 75 O, by which it may be turned. Preferably the hole L is threaded to receive the end of the screw. From the hole K a slot P opens rearward of a width corresponding to the diameter of the body of the screw. The slot P is provided in order that the two parts may be separated without the entire withdrawal of the screw, which would be inconvenient in case the connecting-screw is employed as the hammer-pivot. As thus constructed when it is desired to separate the two parts the screw is 80 withdrawn so far as to take its tip out of connection with the cheek on that side and to withdraw the conical neck from the countersink of the hole K, and, as seen in broken 85 lines, Fig. 2, the parts may then be withdrawn, the slot P permitting that part to pass freely from the body of the screw, and when the parts are again set together the screw is returned to interlock the two parts at the rear 90 and the conical neck acts, in connection with the countersink, as a cam tending to draw the two parts together. Thus a firm connection is made between the two parts, but leaving them always in a condition for convenient 95 and easy separation.

While preferring to construct the one cheek

with a slot P, so as to permit the separation without the entire removal of the screw, the slot and the countersink may both be omitted, as seen in Fig. 5, in which case it would require substantially the entire removal of the screw before the parts could be separated.

While illustrating the invention as applied to an arm of the Winchester repeating character, it will be understood that the invention is not to be limited to any particular construction of the receiver, it being adapted to receivers generally.

I claim—

1. The herein - described improvement in firearms, consisting in a receiver carrying the barrel at its forward end, the sides or cheeks of the receiver made as a part of such forward end, the rear and bottom portion of the receiver adapted for attachment to the stock and separable from the said forward part and cheeks and so as to set between the cheeks, the forward end of the said bottom portion of the receiver constructed with a tenon and the forward part of the receiver constructed with a corresponding mortise to interlock with said tenon when the parts are set together, combined with a screw or pin through the said cheeks and rear part of the receiver, substan-

tially as described, and whereby the said parts are made separable.

2. In a firearm, a receiver made in two parts, the forward part carrying the barrel and the two sides or cheeks of the receiver, the rear portion carrying the stock, with a projection therefrom forming the bottom of the receiver, the said projection constructed with tenon at its forward end and the forward portion of the receiver with a corresponding mortise to interlock with said tenon, the cheeks and receiver constructed with a screw hole transversely through them at the rear, one cheek constructed with a slot opening rearward from the said hole and the said slotted hole countersunk, combined with a screw adapted to set through said holes and constructed with a conical neck corresponding to the said countersink, substantially as and for the purpose described.

In testimony whereof I have signed this specification in the presence of two subscribing witnesses.

WILLIAM MASON.
